6 Claims. (Cl. 250—95)

This invention relates to radiographic apparatus and more particularly to improved load adjustment means thereof.

A beam of X-rays or γ -rays, propagated through any heterogeneous object, is differentially absorbed, depending upon the varying thickness, density, and chemical composition of the object. Thus, the nature and, in addition, the activity of a specimen to be radiographically examined must be considered in determining the load adjustments to be made for the examining radiographic apparatus. To this end, in known type of radiography apparatus, as for example, those of the X-ray variety, separate independently actuated adjusting means are provided for adjusting, respectively, the high voltage supplied to the apparatus X-ray tube, the filament current supplied thereto, and the time of exposure. For each particular type of object to be radiographically examined, an optimum range of voltages controlling penetration and of time of exposure are available. For each voltage in this range, there is an exposure value equal to the product of the filament current and duration of the load period, the latter being proportional to the exposure time. Charts, or tables, are available in which the exposure values are plotted graphically against, or tabulated for, different thickness of specimens of a particular composition for these different voltages. The adjustment of the high voltage value is generally determined by the nature of the object in which the factors of its composition and thickness are considered in relation to beam penetration. The adjustment of the load period generally involves the consideration, *inter alia*, of the activity, i.e. relative movement, of the specimen in relation to the optimum definition obtainable for the radiograph. Thus, with a knowledge and/or observation of the thickness, and composition of a particular object, a plurality of voltages within the aforesaid range are available from which to choose the tube voltage adjustment, and the determination of which of these voltages is the proper voltage to choose for the particular specimen is often difficult for the operator to resolve. Once a single voltage has been selected, then consultation of the graph or table will yield the required associated exposure value. However, since this exposure value is the product of two variables and is equal to a constant, for a given voltage value, a plurality of combinations of time and current values are likewise available and further compound and complicate the operator's selection of adjustments. Furthermore, the tabulated or plotted exposure values are generally based on the maximum permissible filament current which may not always be the most efficient value for a particular combination of the variable factors involved. Thus, if the time of exposure is next selected after selection of the operating voltage, a maximum filament current adjustment is derived based on an exposure value obtained from the graph or table. Radiographic apparatus of the prior art are known which provide automatic compensation means for adjusting the filament current in response to the preselected adjustments of the tube voltage and preselected time of exposure. However, these automatic compensation means of the prior art apparatus are equally unsatisfactory since the filament current is automatically adjusted to limit the current to the maximum permissible value which, as aforesaid, may not always be the most efficient setting.

2

It has been found to be more efficacious in some of the prior art apparatus to adjust the tube voltage and the product of the tube current and load period instead of adjusting the tube voltage and the load period with the quality of a radiograph provided by such apparatus being mainly determined then by the tube voltage and this product, referred to, hereinafter, as the milliamperesecond product (ma.-sec.-product). Therefore, these known X-ray apparatus usually comprise an indicating device for the ma.-sec.-product. Thus, the control of an apparatus having relatively independent adjusting means becomes more complicated since not only the maximum permissible current but also the ma.-sec.-product varies with the adjustment of time. In a known device comprising a current adjusting means coupled with a voltage adjusting means and time adjustment means, the time is adjusted to the shortest possible duration for each selected value of the ma.-sec.-product, which, however, does not necessarily always yield the most efficient combinations.

Moreover, various safety members to prevent overloading of the X-ray tube have been suggested in the prior art, which members produce a monitoring signal in the event of an erroneously chosen adjustment and/or prevent the X-ray apparatus from becoming operative. However, the aforesaid disadvantages are only partly obviated, since the efficient choice of the load magnitudes is not facilitated.

An object of this invention is to provide radiographic apparatus which provides for the selection of various load adjustments which will yield the most efficient combination for each particular specimen to be examined.

Accordingly, this invention features a coupling means having a first position which couples the current adjusting means and time adjusting means of an associated radiographic apparatus in relative responsive relationship with each other to maintain the product of the magnitude of the signal current and time period constant whenever either of these adjusting means is adjusted and a second position which couples these adjusting means in an independent relationship with each other whenever either of these two adjusting means is actuated.

Another feature of this invention is the provision of a safety means to prevent overloading of the apparatus due to an incorrect combination of adjustments of any of the adjusting means provided in the apparatus.

The above-mentioned and other features and objects of this invention will become more apparent by reference to the following description taken in conjunction with the accompanying drawing, in which:

FIG. 1 is a schematic diagram partially in block form of the radiographic apparatus of this invention; and

FIG. 2 is a partial structural diagram of an embodiment of the radiographic apparatus of this invention.

Broadly, the radiographic apparatus of this invention comprises a device, generally denoted by the reference letter A, FIG. 1, adapted to produce a beam of rays for radiographic inspection of an object (not shown). Associated with the device A are a suitable source of signal potential, a suitable source of signal current, and a timing means, generally denoted by the reference letters B, C and D, respectively, FIG. 1. Various adjusting means for the sources B and C, and timing means D are also provided and are indicated generally in FIG. 1 by the reference letters E, F, G, respectively. A coupling means H is provided which has two positions, one of which couples the signal current and timing adjusting means in relative responsive relationship with each other to maintain the product of the magnitude of the signal current and time period constant whenever either of these two adjusting means is adjusted and the second position of which couples these two adjusting means in independent-

ent relationship with each other whenever either one of them is adjusted, as will be explained in greater detail hereinafter. A safety means, illustrated in FIG. 1 generally by the reference letter J, is also provided which prevents overloading of the apparatus of FIG. 1 in the event any of the three adjustments are invalidly combined as will also be explained in greater detail herein-after.

Referring to FIG. 1 in greater detail, an electron discharge device for generating a beam of rays for radiographic inspection of an object (not shown) is illustrated, by way of example only, as a tube 10 adapted for generating X-rays. The device has a collector and emitter electrode adapted to produce the beam of rays from electrons emitted from the emitter electrode, in a manner well known to those skilled in the art and are illustrated as the anode and cathode electrodes 12, 13, respectively, of tube 10. To provide a source of high voltage for tube 10, the secondary winding 11 of a high voltage transformer 8 is shunted across the anode electrode 12 and cathode electrode 13 of tube 10. The primary winding 7 of transformer 8 is coupled, via various adjusting means and/or switching means, to the conductors 1, 2, which represent voltage mains connected to a suitable source, not shown, of signal potential, as will be described in greater detail herein-after.

The filament current for tube 10 is provided by filament-current transformer 15 whose secondary winding 14 is coupled to the cathode electrode 13 in a manner well known to those skilled in the art. The primary winding 16 of transformer 15 is coupled, via current adjusting means F, illustrated, for example, as an adjustable rheostat 17, and via voltage stabilizer 18 and switch 17', to the conductors 1, 2. Voltage stabilizer 18, illustrated schematically in block form, is provided to compensate for fluctuations in the signal voltage appearing in the conductors 1, 2, when switch 17' is placed in the closed position.

To control the load period of the tube 10, i.e. the time of exposure, timing means D is associated with the tube 10 and has adjusting means G to adjust the length of time that the high voltage of transformer 8 is applied to tube 10. For example, as illustrated in FIGURE 1, the timing means comprises an electrically operated adjustable timing switch 19, illustrated in block form, which is coupled to the conductors 1, 2 via switch 19'. The adjusting means 20, illustrated as an adjusting arm of switch 19 is positioned to provide some predetermined finite load period, during which period the coil 21 of an electromagnetic switch is energized causing the switching element 22 to close contacts 22', which are located, for example, in the input circuit of the primary winding 7 of transformer 8, and apply the high voltage to the tube 10. Upon expiration of the adjusted predetermined period, coil 21 is de-energized and switching element 22 opens contacts 22' removing the high voltage supplied by transformer 8 from tube 10.

The voltage adjusting means associated with the tube 10 comprises a control transformer illustrated, by way of example only, as an autotransformer 3 having an adjustable input 5 coupled to the conductors 1, 2 via switch 3' and adjustable matching resistor 4. A meter 6 is shunted across the input to transformer 3 and indicates the magnitude of the signal there applied. An adjustable output means is provided on transformer 3 and is illustrated, by way of example only, as having several variously spaced taps connected to the contacts of a stepping switch 9, the latter having a movable arm 9', the position of which determines, inter alia, the magnitudes of the signal applied to the input of the primary winding 7 of transformer 8. It is to be understood, however, that the output means of transformer 3 illustrated in FIG. 1 are chosen by way of example only and that adjustable output means of a continuous type, such as those comprising a movable wiper arm adapted to sweep the output wind-

ing of the transformer 3, and similar to the adjustable input means 5, may also be utilized, in lieu of the illustrated tapped output winding of transformer 3 and stepping switch 9, in a manner well known to those skilled in the art.

In order to compensate for certain voltage losses that occur due to changes in the power consumption and filament current caused when adjustments are made in the voltage and/or current adjusting means, voltage regulation means for tube 10 are provided. For example, to compensate for voltage losses caused by adjustment of the voltage adjusting means and voltage losses caused by the adjustment of the current adjusting means, serially connected adjustable resistor 24 and an auxiliary winding 25 associated with the transformer 3 are, respectively, provided. The adjustable resistor 24 has its movable arm 23 actuated by the movement of arm 9' of the voltage adjusting means, as for example by a mechanical means such as a shaft, illustrated by dashed line 32, to which the arms 9' and 23 are commonly ganged. The resistor 24 is so arranged that the resistance thereof varies, in response to a movement of arm 9', inversely proportional to the magnitude of the signal potential applied across the electrodes of tube 10 and, thus, compensates for any voltage loss which occurs because of the change in power taken by tube 10 when arm 9' is moved. To compensate for voltage losses which occur because of the displacement of movable arm 27 of rheostat 17 of the current adjusting means, the auxiliary winding 25 is provided with a plurality of output taps which are connected to the respective contacts of a stepping switch 26. The stepping switch 26 has a movable arm 26' which is actuated by the movable arm 27 of rheostat 17 as, for example, by a mechanical connection such as a shaft, illustrated as the dashed line 30, to which the arms 27 and 26' are commonly ganged. The position of arm 26' with respect to the winding 25 is such that a voltage of sufficient magnitude will be induced in the input circuit to the high voltage transformer 8 which will compensate for the associated voltage loss caused by the movement of arm 27. It is to be understood, however, that the output means of auxiliary winding 25 may be of a continuous type in lieu of the illustrated tapped output winding 25 and stepping switch 26. As mentioned hereinabove, between time adjusting means G and current adjusting means F, coupling means H is provided which depending on its relative position allows these two means, F and G, to be either in a first position of responsive coupling relationship relative to each other or in a second position of independent coupling relationship with each other whenever either of the means F and G are adjusted. Thus, an operator, after selecting a suitable operating voltage for tube 10 by adjustment of the arm 9' and/or input means 5 and with the coupling means 28 in the aforescribed second position, could individually adjust the time and current adjusting means via adjusting means 20 and 17, respectively, to yield a ma.-sec.-product as found from the tables or charts associated with the specimen to be examined. Thereafter, the coupling means 28 could be placed in its first position and either the time or current adjusting means be further adjusted to yield the most efficient adjustment combination and, at the same time still maintain the selected ma.-sec.-product constant, i.e., for a given or preselected exposure value. In the alternative, the means 28 may remain in its second position so that each of either the time adjusting means or current adjusting means may be individually and independently adjusted for a given adjustment of the other so as to provide an efficient adjustment combination which will yield an exposure value that may or may not be equal to the exposure value derived from the chart or tables. To help facilitate the selection of the magnitudes of the various adjusting means, the coupling means H, as well as the individual adjusting means E, F, G,

may be suitably calibrated, in a manner well known to those skilled in the art.

To prevent overloading of tube 10 because of any invalid adjustment of adjusting means E, F, G, a safety member J, as afore-mentioned, is provided and may comprise, for example, a series of inter-related networks such as the reference sources 50, 53 and adjustable resistors 49, 52, 54, 55 whose movable members are in responsive coupling relationship with the respective movements of the adjusting means to provide a reference signal and a signal proportional to the selected adjusted load values. The signals are compared via suitable comparison means 59, illustrated in block form and of a type well known per se, which in turn may actuate a signal indicator system 60, also illustrated in block form, which may automatically prevent operation of tube 10 or which may actuate some visible and/or audible indicator warning device.

Referring to FIGURE 2, the structure of an embodiment of the radiographic apparatus of this invention in which a mechanical coupling means is utilized, is partially illustrated. Accordingly, through the wall 29, which may be the cover of an operator's control desk, are disposed three shafts 30, 31 and 32, each of which is provided with an adjusting knob 33, 34 and 35, respectively. The tube current of tube 10, FIG. 1 is adjusted by the movement of the knob 33 and the tube voltage by movement of the knob 35. Knob 34 adjusts the load period of tube 10. Affixed to the shafts 30, 31 and 32 are the sliding contacts of movable arms 27, 28 and 9, respectively, which are associated with their respective elements, to wit, rheostat 17, adjusting means 20 and stepping switch 9. Also coupled to the shaft 30 is a movable arm 26 of the stepping switch 26 which, as aforesaid, coacts with the auxiliary winding 25 to compensate for voltage losses which occur due to the movement of movable arm 27 of rheostat 17. Similarly, on the shaft 32 is coupled the movable arm 23 of the resistor 24 which, as aforesaid, is provided to compensate for voltage losses due to the movements of arm 9 of stepping switch 9 associated with the control transformer 3.

Between the shafts 30 and 31, a coupling member, illustrated generally by reference numeral 28, comprises a differential gear system 36. The gears 37 and 39 are keyed, respectively, to shafts 30 and 31 and engage respectively the gears 38 and 40, the latter being keyed, respectively, to shafts 38a and 40a. Keyed to the shafts 38a and 40a are the gears 36a and 36b, respectively, of the differential gear system 36. The differential gear system 36 is housed in a rotatable drum 41 which has a shaft 41a disposed thereon to support the gears 36c and 36d which are meshed with gears 36a and 36b. Associated with the drum 41 is a gear 43 which is adapted to be engaged by the gear 44, the latter being keyed to a shaft 45 which is axially movable along its longitudinal axis by depression of the knob 46 attached to the end thereof. The rotatable drum 41 may include, along the periphery thereof, a scale 42 calibrated with reference markings proportional to the product of different signal current magnitude and time period combinations. To this end, the shaft 45 may be rotatable and, by depression and movement of the knob 46, causes the gears 43 and 44 to mesh so that the drum 41 will be driven. An opening 47 is provided on the wall 29 for observation of the markings of scale 42.

In operation, the coupling means of FIG. 2 comprises a first position in which the shaft 45 is depressed to engage gears 43 and 44 and prevent the rotatable member 41 from rotating about the gears 36a and 36b and allow, whenever either of the adjusting means associated with the shafts 30 and 31 are actuated by movements of their respective knobs 33 and 34, the movements of these shafts 30, 31 to be transmitted to the other shaft via gear system 36 and gears 37 to 40. In the second position of the coupling means 28, the gears 44 and 43 are disengaged causing the drum 41 to be in responsive relationship with

movement of either of the shafts 30 or 31. In addition, in the second position the shafts 30 and 31 are in independent coupling relationship with each other as the movement of either gear of the pair 36a or 36b will not be transmitted through the gears 36c and 36d to the other gear of the pair.

Alternatively, the drum 41 may be driven in the first position to indicate a ma.-sec.-product as derived with the aid of a chart or table.

10 To find the combination in which the load period is at a minimum for a given tube voltage either for a maximum permissible tube current or a given percentage thereof, a suitable safety member means is utilized. For example, the safety member J, FIG. 1, is illustrated therein and in FIG. 2 as comprising a potentiometer 49 connected to a suitable reference source 50. The position of movable arm 48 of potentiometer 49 is disposed on the shaft 32, so that any voltage adjustment to tube 10, FIG. 1, causes a signal to be derived at the output of potentiometer 49 which is proportional to the logarithm of the magnitude of the signal voltage applied to tube 10. A second potentiometer 52 is also coupled to the reference source 50, and the movable arm 51 thereof is actuated by movement of the shaft 31. The signal derived from the output of the potentiometer 52 is made proportional to the logarithm of the maximum permissible kilowatt-second product for tube 10. The signals derived from potentiometers 49 and 52 are combined in an opposing sense, so that their difference represents a signal whose magnitude is proportional to the logarithm of the maximum permissible ma.-sec.-product and is supplied as a reference signal to the input of a comparison circuit 59 to provide a threshold level therefor.

35 Two serially connected potentiometers 54 and 55, are serially connected to voltage source 53. The movable arm 56 of potentiometer 54 is actuated by shaft 30 in response to movements of the circuit adjusting means causing a signal to be derived at the output of potentiometer 54 proportional to the logarithm of the magnitude 40 of the signal current applied to tube 10. The other potentiometer has its movable arm 57 responsive to movements of shaft 31, via a suitable coupling means 58, illustrated in Fig. 2, by way of example only, as a belt and pulley system, causing a signal to appear at the output thereof proportional to the logarithm of the adjusted load period. The signals derived from the potentiometers 54 and 55 are combined in an aiding sense to provide a signal proportional to the logarithm of the adjusted ma.-sec.-product for tube 10 which, in turn, is fed to the comparator 59 where it is compared with the reference signal derived from potentiometers 49 and 52. Comparator 59 provides a signal which is coupled to a signal indicator system 60 which may be a meter calibrated, for example, to indicate, in percentages, the relationship of the adjusted ma.-sec.-product to the maximum permissible ma.-sec.-product.

45 While I have described above the principles of my invention in connection with specific apparatus, it is to be clearly understood that this description is made only by way of example and not as a limitation to the scope of my invention as set forth in the objects thereof and in the accompanying claims.

50 What is claimed is:

1. A radiographic apparatus comprising an electron 55 discharge device having a collector electrode and an emitter electrode adapted to produce a beam of X-rays for radiographic inspection of an object, a first source of potential coupled to said electrodes to provide an operating potential for said device, a second source of current coupled to said emitter electrode to heat said emitter electrode, timing means to uncouple said first source from said electrodes after a given time period, first adjusting means coupled to said first source to adjust the magnitude of said operating potential, second adjusting means 60 coupled to said second source to adjust the magnitude

of said heating current, third adjusting means coupled to said timing means to adjust the length of said time period, and coupling means having a first position for coupling said second and third adjusting means in relative responsive relationship with each other to maintain the product of the magnitude of the emitter current and time period constant whenever either of said second and third adjusting means is adjusted and having a second position for decoupling said second and third adjusting means from each other whereby either of said second and third adjusting means can be adjusted independently of the other. 10

2. A radiographic apparatus according to claim 1, wherein said apparatus further comprises safety means to prevent overloading of said device comprising means for producing a first potential proportional to the logarithm of the operating voltage applied to said discharge device, means for deriving a second potential proportional to the logarithm of the maximum permissible kilowatt-second product for said discharge device, means for combining said first and second potentials to obtain a first resultant potential proportional to the logarithm of the maximum permissible current-second product for said discharge device, means for deriving a third potential proportional to the logarithm of the current in said discharge device, means for producing a fourth potential proportional to the logarithm of a selected exposure time for said discharge device, means for adding said third and fourth potentials to produce a second resultant potential, means for supplying said first and second resultant potentials to a comparison means to obtain an indicating signal, and indicating means responsive to said indicating signal. 30

3. Apparatus according to claim 1, wherein said coupling means comprises a differential gear system having a pair of first and second gears, said first and second gears being mounted in responsive coupling relationship with said second and third adjusting means, respectively, a third gear meshed with each of said first and second gears, said coupling means further comprising control means 40 having a first and second position corresponding to said first and second positions, respectively, of said coupling means, a rotatable member coupled to said differential gear system and adapted to be driven independently by each of said first and second gears in said second position of said coupling means, a shaft disposed on said rotatable member to support said third gear, said control means in said first position being arranged to block rotation of said

5

10

15

25

30

35

40

45

rotatable member thereby to allow said third gear to be driven independently by either gear of said pair of first and second gears thereby to drive the other gear of said pair of gears.

4. Apparatus according to claim 3, wherein said rotatable member comprises a drum having a fourth gear disposed thereon, and said control means comprises a rotatable shaft on which is mounted a fifth gear adapted to be meshed with said fourth gear in said first position.

5. Apparatus as described in claim 4 wherein said rotatable drum comprises an indicator scale disposed on the periphery thereof, said scale being calibrated with reference markings proportional to the product of different combinations of current magnitudes and time periods.

6. Control apparatus for a radiographic device comprising an electron discharge device having a collector electrode and an emitter electrode and adapted to produce a beam of electromagnetic energy for radiographic inspection of an object, said control apparatus comprising means for energizing said discharge device, said energizing means comprising means for supplying an operating potential to said electrodes and means for supplying a current to said emitter electrode, timing means for de-energizing said discharge device after a given time period, first adjusting means for varying the magnitude of said operating potential, second adjusting means for varying the magnitude of said emitter current, said timing means comprising third adjusting means for varying said time period, and coupling means having a first position for coupling said second and third adjusting means in relative responsive relationship with each other to maintain the product of the magnitude of the emitter current and time period constant whenever either of said second and third adjusting means is adjusted and having a second position for decoupling said second and third adjusting means from each other whereby either of said second and third adjusting means can be adjusted independently of the other.
